UNITED STATES PATENT OFFICE.

JOSEF TANCZER, OF BUDAPEST, HUNGARY.

HOE FOR CULTIVATING-MACHINES.

1,227,090.

Specification of Letters Patent. Patented May 22, 1917.

Original application filed June 18, 1913, Serial No. 774,297. Divided and this application filed July 6, 1914.
Serial No. 849,105.

To all whom it may concern:

Be it known that I, JOSEF TANCZER, merchant, subject of the King of Hungary, residing at 27 Alkotmány utca, Budapest V, Hungary, have invented certain new and useful Improvements in Hoes for Cultivating-Machines, of which the following is a specification.

My invention relates to hoes for ground-cultivator-machines such as described in my application Ser. No. 774,297, filed June 18, 1913, of which this application is a division, and consists in a hoe, the stem of which is rigid in the plane of the movement of the hoe, but a little elastic in the plane perpendicular to the said plane.

The accompanying drawing shows examples of the hoe constructed according to my invention.

Figure 1 is one side view of a constructional form of the hoe,

Fig. 2 a plan view thereof,

Fig. 3 a side view of a modification and

Fig. 4 a plan view thereof.

According to my invention the stem of the hoe is rigid in the direction of the movement of the hoe and has a small elasticity in a direction perpendicular thereto.

The hoe-stems as illustrated in Figs. 1-4 of the drawing, consist of two plates 22 attached to sleeves 9 and having supported between them an elastic plate 23 of steel, rotatable around a bolt 24'. The sleeves 9 are secured to the outer sides of the plates 22 and are mounted on a shaft 7 of the machine, around which the hoe-stems are arranged. The elastic plate 23 of steel is provided on both sides of its outer end with proper hoe-tools 24.

By making the plate 23 of steel the hoe-stem may yield when lateral pressures occur and in this case the hoe-stem can yield within certain limits, without causing deformation of the stems of the hoes. The elasticity of the stems of the hoes may be increased

45 by the use of separate flat-springs 29 (Figs.

1 and 2), or this arrangement may serve to make the stems somewhat more rigid against lateral bending, without destroying the elasticity of the stem. In the constructional form illustrated in Figs. 3 and 4 a double plate 23 is provided which has supported between its two parts a rotatable circular blade 30. The latter has for its object to facilitate the cutting into the ground, which cutting is performed in the constructional form above described by the steel-plate 23. By the use of the said circular blade the resistance is lowered.

The hoe tools can be fastened to the stem 60 not only in the illustrated manner but otherwise also for instance between two steel-plates 23 in the same manner as the circular blade 30 which is essentially a cultivator-tool also.

25 designates a bore in the two plates 22, through which bore may be passed a bolt. In order to clear this bolt, when swung about the pivot 24' the steel plate 23 is provided with a curved slot 27, as clearly shown in 70 Figs. 1 and 3. 28 is another bore, passing through all the plates 22, 23. Through this bore a bolt made of wood or similar material, is passed, which bolt upon the plate encountering a great resistance in the ground 75 will break so that the plate 23 can swing about its pivot 24' as stated.

Claim:

A hoe for rotary cultivating machines comprising a rigid stem formed of a pair of 80 spaced plates, a laterally resilient member mounted between the plates and carrying hoeing elements, a pivot pin connecting the member to the plates, and releasable means normally restraining the member against 85 rotation of the pivot pin.

In testimony whereof I affix my signature in presence of two witnesses.

JOSEF TANCZER.

Witnesses:

FÜLÖ PLOHÖN,
HUGH KEMENY.
